Primary Examiner — Lilyana Bekic*Assistant Examiner* — Mary Shannon Malley(74) *Attorney, Agent, or Firm* — Eric Kelly**CLAIM**

What is claimed is the ornamental design for a face soaking device, as shown and described.

DESCRIPTION

FIG. 1 depicts a perspective view of a face soaking device; FIG. 2 depicts a front view thereof; FIG. 3 depicts a back view thereof; FIG. 4 depicts a left-side view thereof; FIG. 5 depicts a right-side view thereof; FIG. 6 depicts a top view thereof; and, FIG. 7 depicts a bottom view thereof.

The broken lines in the figures depict portions of the face soaking device that form no part of the claimed design.

1 Claim, 7 Drawing Sheets See application file for complete search history.
